UNITED STATES PATENT OFFICE.

GEORGE H. SMITH, OF FOREST HILL, NEW JERSEY, ASSIGNOR TO UNION TYPEWRITER COMPANY, OF JERSEY CITY, NEW JERSEY, A CORPORATION OF NEW JERSEY.

TYPE-WRITING MACHINE.

No. 918,480.

Specification of Letters Patent.

Patented April 13, 1909.

Original application filed December 29, 1903, Serial No. 186,976. Divided and this application filed October 8, 1906. Serial No. 338,007.

To all whom it may concern:

Be it known that I, GEORGE H. SMITH, citizen of the United States, and resident of Forest Hill, in the county of Essex and State of New Jersey, have invented certain new and useful Improvements in Type-Writing Machines, of which the following is a specification.

My invention relates to means for guiding the type bars to the printing point and the object of said invention is to provide simple and efficient means of the character specified.

To the above and other ends which will hereinafter appear, my invention consists in the features of construction, arrangements of parts and combinations of devices to be described in the following specification and particularly pointed out in the appended claims.

20 In the drawings, Figure 1 is a central, vertical, front to rear sectional view showing a sufficient number of parts of one form of typewriting machine to illustrate my invention in its application thereto. Fig. 2 is a 25 fragmentary detail plan view of a type guide showing a type bar in place in the guide; the view looking in the direction of the arrow *a* in Fig. 1. Fig. 3 is a fragmentary detail front elevation of the type guide showing a type 30 bar in place in the guide, the view looking in the direction of the arrow *b* in Fig. 1.

The present invention is a division of my application Serial No. 186,976, filed December 29th, 1903, which in turn is a division of 35 my application Serial No. 13,773, filed April 21st, 1900, said last mentioned case being a division of my application Serial No. 640,951, filed June 16th, 1897.

The base 1 of the machine is surmounted 40 by upright standards or posts 2, 3. Key levers 4 are provided with finger keys 5 and are pivoted within the base of the machine upon a single pivot wire 6 that extends from side to side of the base. A second rod or wire 7 45 extends from side to side of the base and cooperates with a rounded portion 8 on each of the key levers 4, which rounded portions are substantially concentric with the pivot wire 6. The key levers are guided in their vertical 50 movements by a guide comb 9 near the front of the machine. Each of the type bars 10 of the segmentally arranged series of type

bars (only one of which is shown in Fig. 1) is pivoted at 11 to an inclined type bar segment 12 supported on the posts 2. The type bars 55 are adapted to swing rearwardly to the printing position as shown in dotted lines in Fig. 1 and to strike upon the upper and forward face of the platen 13 diagrammatically shown in Figs. 1 and 3. The heel of each type bar 60 is connected at 14 to a link 15 pivoted at its upper end 16 to a substantially horizontally disposed sub-lever 17 pivoted at 18 to supports 19 secured to a plate 20 mounted on the posts 3. The forward end of each sub-lever 65 17 is pivoted to a depending link 21 connected at 22 to the associated key lever 4. A restoring spring 23 is connected at one end to a sub-lever 17 and at its opposite end to a fixed pin or finger 24. A depression of a key 70 lever will move the associated type bar from the full to the dotted line position shown in Fig. 1, the type bars being supported in the normal position by a type rest 25.

Rigidly secured to the inclined type bar 75 segment 12 are upwardly and inwardly projecting arms 26 which extend toward each other and terminate forward of the printing point. These fixed arms carry anti-friction rollers 27 pivoted to the arms at 28 and 80 forming a so-called center guide with which the type bars coöperate in their movements to the printing position. The adjacent contact or guiding surfaces of these anti-friction rollers are spaced apart at a distance which 85 corresponds substantially to the width of that portion 29 of each type bar which is received between the anti-friction rollers, as shown in Fig. 3, in order that the flat parallel sides of the portion 29 of each type 90 bar may be received between and coöperate with the rollers to properly guide each type bar in its approach to the printing position. The parallel fixed axes of the anti-friction rollers are so disposed that when a type bar 95 contacts with the rollers in the movement of the bar to or from the printing position the rollers may receive a turning movement around their axes through the contact of the type bar with the rollers. The peripheries 100 of the rollers curving toward each other as shown in Fig. 3, receive and properly deflect the approaching type bar to the proper position between the rollers without obstructing

the movement of the bar, thus effectively directing the bar so that proper registration with the printing point will be effected. By the employment of the anti-friction rollers 27 wear upon the contact faces of the guide is distributed over greater and constantly changing surfaces and there is less liability of obstructing the type bar in its movement to printing position and also less liability of the type bar sticking and jamming in the guide than when fixed guiding surfaces are employed.

While I have referred herein to the parts 27 as anti-friction rollers and I prefer to employ rollers of the character shown in the drawing with fixed pivots around which the rollers turn, it should be understood that the term "anti-friction rollers" is employed in a generic sense and refers to various forms of anti-friction rollers whether they be in the nature of anti-friction balls or rollers of the form shown herein.

Various changes may be made without departing from the spirit and scope of my 25 invention.

What I claim as new and desire to secure by Letters Patent, is:—

1. In a typewriting machine, the combination of type carriers, and a type guide carrying anti-friction rollers between which the type carriers are received and by which they are guided in the movements thereof to the printing point without arresting the movements of the type carriers, the thickness of 30 those portions of the type carriers which coöperate with the said rollers corresponding to the distance between those portions of the

rollers with which a carrier is in contact when it is in the printing position.

2. In a typewriting machine, the combination of type carriers, and anti-friction rollers which turn on fixed axes and between which the type carriers are received and by which they are guided in their movements to the printing point without arresting the type carriers in their movements to the printing position, the thickness of those portions of the type carriers which coöperate with said rollers corresponding approximately to the distance between those portions of the rollers with which a carrier is in contact when it is in the printing position.

3. In a typewriting machine, the combination of type carriers each having a guiding portion with flat substantially parallel sides, 55 and a guide having anti-friction rollers co-operating with the flat substantially parallel sides of the guiding portion of each type bar.

4. In a typewriting machine, the combination of type carriers each having a guiding portion with flat substantially parallel sides, 60 and a guide having anti-friction rollers which turn on fixed parallel axes and coöperate with the flat substantially parallel sides of the guiding portion of each type bar.

Signed at the borough of Manhattan, city of New York, in the county of New York, and State of New York, this 6th day of October, A. D. 1906.

GEORGE H. SMITH.
